UNITED STATES PATENT OFFICE

EMIL W. CARLEWITZ, OF JERSEY CITY, NEW JERSEY

GARMENT HANGER

Application filed June 21, 1927. Serial No. 200,321.

This invention relates to garment hangers in general and particularly to the kind adapted to be used outdoors.

The prime object of my invention is to provide a device of this kind which is capable of being suspended from a clothes line in such a manner that it cannot voluntarily, or by the force of a strong wind, detach itself from the line, and furthermore, having means for securely holding a garment, suspended from the bar of the hanger, against leaving that bar, whether unintentionally or when agitated by a strong breeze.

The foregoing principal and further objects will be more fully apparent from the following description and the accompanying drawings, forming part of this disclosure, but by no means intended to limit the invention to the showing.

20 Referring to the drawings, Figure 1 represents a side elevation of a garment hanger, and

Figure 2 is a bottom view thereof.

In the drawings, numeral 10 denotes a 25 hanger bar, suspended by hook member 11, which comprises a double loop, consisting of an outer loop portion 12 and an inner loop portion 13. The latter is a continuation of the former, and is shaped similarly 30 and arranged eccentrically, relative to the former. It will be seen that the outer loop portion is provided with a cord receiving notch 14, adapted to hold in place a cord or clothesline, indicated at 15. The free end of 35 the inner loop portion is somewhat rounded inwards so as to provide an easy entrance for the cord, in the direction indicated by an arrow.

At one side of bar 10, there is attached a 40 double clamping member 16, formed from a flat spring and curved or shaped to follow approximately, the contour of the bar member 10, as can be plainly seen in Figure 1. The center portion 17 of the clamping member 45 is depressed, and serves as attaching portion for the clamping member. The free ends 18 of the clamping member extend in the direction towards the ends of the bar member, but terminate short of those, and are 50 semi-looped upwards, as indicated at 19.

At their looped ends and the sides facing the bar, there are provided felt pads 20, intended not only to increase friction between a garment and the clamping member, but also preventing undue damage which may be 55 caused by the bare end of the clamping member.

Operation

My device is plainly intended for airing clothes. The garment is hung over the hanger bar as usual, but the end of the garment, on the side where the clamping member is secured, is brought under the arms of that member, and held thereby against leaving the bar. Now the clothesline or a cord from which the hanger is to be suspended, is brought in at the point marked by the arrow, and forced into the notch 14.

Since the inner portion 13 of the hook is 70 resilient, it will permit the cord to easily pass into the notch. However, the moment the cord has imbedded itself within that notch, the portion 13 will bear against the lower part of the cord or line, and will clamp it there in 75 place.

When it is desired to remove the hanger from the line, the free end of the inner hook portion 13 has to be depressed so as to loosen its grip upon the line, and permit the latter 80 to be drawn out.

While I have shown a specific construction of my device, be it understood that improvements and changes may be made within the scope of my invention, for which I claim:

1. In a garment suspending device having means for securing a garment against disengagement therefrom, the combination with a hanger bar, of a hook member comprising an outer loop portion, an inner loop portion adjacent thereto, said outer loop portion having a cord receiving recess and a cord secured therein, said inner loop portion bearing against said cord.

2. In a garment hanger including a garment receiving bar and means for securing a garment against disengagement from said bar, the combination with the bar, of a suspension hook comprising an outer, resilient loop member, an inner resilient loop member 100

bent against and in substantially parallel relation with the inner face of said outer loop member, a cord engaging recess formed in the latter a cord secured in said recess, said inner loop member bearing against the cord in said recess, thereby clamping the cord, held therein, against disengagement from the loop.

3. In a garment hanger as per claim 2, said inner loop member being shorter in length than the outer loop member and having its free end deflected from the inner face of said outer loop member for permitting the insertion between the loop members of a cord or the like.

15 15 Signed at New York in the county of New York and State of New York this 9th day of June, A. D. 1927.

EMIL W. CARLEWITZ.
